FOREIGN PATENT DOCUMENTS

GB 2098572 A 3/1982

Primary Examiner — Carol P Rademaker

(74) Attorney, Agent, or Firm — Novak Druce Connolly Bove + Quigg LLP

CLAIM

The ornamental design for a bottle, as shown and described.

DESCRIPTION

FIG. 1 is a perspective view of a bottle;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines in the drawings illustrate a portion of the bottle which forms no part of the claimed design.
